(57) **CLAIM**

The ornamental design for a curtain rod as shown and described.

DESCRIPTION

FIG. 1 is a front, top perspective view of a curtain rod showing my new

FIG. 2 is a rear, bottom perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The curtain rod is shown with symbolic breaks in its length. The dot-dash broken lines represent symbolic breaks and any portion of the curtain rod between the break lines forms no part of the claimed design. The evenly dashed broken lines shown in the drawings illustrate portions of the curtain rod that form no part of the claimed design.

1 Claim, 8 Drawing Sheets
